Patented Nov. 21, 1922.

Inventor
Henry E. Pelletier
By his Attorney
Frank C. Fischer

UNITED STATES PATENT OFFICE.

HENRY E. PELLETIER, OF NEWARK, NEW JERSEY, ASSIGNOR TO PELLETIER PRODUCTS MFG. CO., INC., OF ELIZABETH, NEW JERSEY, A CORPORATION OF NEW JERSEY.

PUMP.

Application filed March 2, 1920. Serial No. 362,737.

To all whom it may concern:

Be it known that I, HENRY E. PELLETIER, a citizen of the United States, residing in the city of Newark, county of Essex, and State 5 of New Jersey, have invented certain new and useful Improvements in Pumps, of which the following is a full, clear, and exact description, such as will enable others skilled in the art to which it pertains to 10 make, construct, and use the same, reference being had to the accompanying drawings, and to numerals of reference marked thereon, forming a part of this specification.

My invention relates to improvements in 15 pumps, more particularly to sealing devices for pumps and the like, and the invention consists in the combinations, arrangements and constructions herein described and claimed.

20 The paramount object of my invention is to provide a very simple pump, in which no bolts are required in order to obtain a strong and durable construction, and in which no sealing gaskets are required in order to secure fluid-tight unions.

25 My invention has for a further object to produce a construction of the above character which may embody an eccentric or a cam drive, and it embodies improved means 30 for adjusting such drive.

For a full understanding of my invention, reference is to be had to the following description, and as well to the illustrative embodiment shown in the accompanying 35 drawing which represents a central vertical section through a structure made in accordance with my invention.

In carrying out my invention, I provide 40 an eccentric casing 1, cast in one piece, and having a relatively large opening 2 in its front head, a relatively long bearing 3 in its back head, and a relatively large opening 4 in its top periphery. The openings 2 and 4 are circular in form and are screw-threaded 45 ed. The bearing 3 is located in axial relation to the opening 2, and extends partly within the eccentric casing and partly exterior thereof as shown.

Screw-threaded into the top opening 4 is

a cylinder 5, cast also in one piece, and having an open bottom end 6, which provides direct communication with the interior of the eccentric casing 1; and it will be understood from an inspection of the drawing that the cylinder is thus secured to the eccentric casing in vertical position, and centrally thereof, so that the axial center of the former would cross the axial center of the latter at right-angles. Where the screw-threaded union occurs, the cylinder is provided with a flange 7, designed to engage over the outer surface of the eccentric casing; and at the region 8, adjacent this flange, both edges of the union are correspondingly tapered with a view of making a fluid-tight joint.

The top or head end 9 of the cylinder is made relatively thick and is provided vertically therethrough with two openings 10 and 11, suitable for receiving the valves 12 and 13, respectively. Each valve has its main body portion screw-threaded in its opening, and has also, adjacent the screw-threads, a tapering portion 14, countersunk in the head to make a fluid-tight connection.

The valve 12 is a suction valve and may be of any ordinary type, through which gas or fluid can be drawn into the compression chamber 15, from an intake pipe 16. The valve 13 commands the exhaust of the gas or fluid, an operation accomplished through an outlet pipe 17. This valve is of the spring-pressed rotary type, and its peculiar features of construction are set forth fully in my application for patent, filed March first, 1920, Serial No. 362,464. It is sufficient here to state that this valve includes a compression spring 18, which normally holds the tapering valve 19 in its seat, the said spring yielding under sufficient pressure exerted on the valve proper, to permit the unseating of the latter, for the discharge of gas or fluid.

The cylinder 5 contains the usual piston head 20, which forms a partition between the combustion chamber 15 and the interior 21 of the eccentric casing. 22 is the connecting rod; and 23 the eccentric collar

which operatively embraces an eccentric 24, engaged on the shaft 25, which is journaled in the long bearing 3 as shown.

Screw-threaded upon the exterior portion 5 of the long bearing 3 is a packing gland 26. The confronting sides of the packing gland 26 and the bearing 3 are tapered as at 27 to provide a chamber in which to confine the packing 28, of any ordinary character. The 10 packing gland 26 has an annular recess 29 in which is screw-threaded the flange 30 of a covering 31. By means of these parts, thus arranged, I provide an oil chamber 32 surrounding the shaft 25, the oil being introduced 15 into the chamber through an opening 33, which is normally closed by a screw plug 34.

The covering 31 is provided with concentric grooves 35, receptive of corresponding 20 projections formed on the face of a gland 36, which, together with a pulley 37, is secured by a key 38 to the shaft 25. Adjacent the shaft 25, the confronting faces of the covering 31 and gland 36 are tapered 25 as at 39 to provide a cavity for the packing 40, which may be of any ordinary character.

Into the opening 2 of the eccentric casing, there is screw-threaded a plug 41, formed on 30 its inner side with an axial projection 42, having a central bore 43. Into this bore is threaded a pin 44 having a rounded end 45, designed to bear on the inner end of the shaft 25. The purpose of this arrangement 35 is to hold the shaft 25 operatively in position, preventing it from shifting longitudinally toward the plug 41, it being observed in this connection that the pin 44 is limitedly adjustable so that the parts may be held in 40 proper relative position with respect to the piston. The plug 41 is provided at 46 with a tapering flange, designed to cooperate with a corresponding taper on opening 2, whereby to effect a tight union. The outer face 45 of the plug 41 is made with a square, or otherwise non-circular projection 47, designed to receive a wrench or the like whereby to effect the turning action.

In assembling the structure, the shaft 25 50 with its eccentric parts is inserted through the main casing opening 2, after which the parts which co-operate to form the stuffing-boxes and the oil-chamber are secured in position. The piston is then operatively 55 connected through the top opening 4, and the cylinder 5 applied. Lastly, the pin 44 is adjusted in the plug 41, and the latter is screwed into position.

By constructing and arranging the parts 60 in the manner described and illustrated, I provide a structure that is easy of assembly, and that avoids the employment of bolts and sealing gaskets, while securing, nevertheless, a strong and durable structure with positively fluid-tight unions.

Experience has demonstrated that the organization above described is a highly efficient one, and while I have shown the preferred embodiment of my present invention, I do not wish to be limited to the exact 70 details of construction shown and described, as obvious modifications thereof, not involving the exercise of invention, may be made by any skilled mechanic, and such departures from what is herein set forth, I 75 consider within the scope and terms of my claims.

Having thus described my invention, what I claim is:—

1. In the herein described pump construction, a one-piece eccentric casing having a front head opening, a back-head bearing projecting both interiorly and exteriorly in alignment therewith and a peripheral opening, a plug screw-threaded into said front- 80 head opening and provided with an adjusting screw, a shaft fitting said bearing and engaging said adjusting screw, a packing gland threaded on the exterior end of said bearing and forming therewith a stuffing- 85 box for the shaft, a covering having threaded engagement with said packing gland, said covering being formed with a rim flange having screw-threaded engagement with the packing gland and forming therewith an oil 90 well for the shaft, and a one-piece open- 95 ended cylinder screw-threaded into said peripheral opening and communicating directly with the interior of the eccentric casing, and a piston in the said cylinder operatively connected with the said shaft. 100

2. In the herein described pump construction, a one-piece eccentric casing having a front-head opening, a back-head bearing projecting both interiorly and exteriorly in alignment therewith provided with a beveled end, and a peripheral opening, a plug screw-threaded into said front-head opening, a shaft provided with a reduced portion extending through the bearing and carrying 110 spacedly therefrom on said reduced portion a keyed gland formed with a disc-shaped gland head having an annular projection, a packing gland mounted on the shaft between said bearing and gland head and having a portion screw-threaded on the bearing and co-operating with the beveled end thereof to form a packing chamber around the shaft, and an oil-chamber covering mounted on the shaft adjacent said disc-shaped head and provided with a beveled region to form therewith a packing chamber around the shaft and provided further with an annular recess for the reception of the annular projection of said head, said last 125 mentioned covering being formed with a rim flange having threaded engagement with the packing gland to form with the latter an oil-chamber around the shaft and a one-piece open-ended cylinder screw-threaded into said 130

peripheral opening and communicating directly with the interior of the eccentric casting and also having valve receiving openings in its opposite or head end, a piston in the said cylinder, and an operating crank shaft journaled in the said bearing and connected to said piston.

This specification signed and witnessed this 25th day of February 1920.

HENRY E. PELLETIER.
